Fig. 1

A perspective view of a stack of 85' sections of a stackable frame. The stack is shown from a three-quarter angle, revealing the vertical ribs and the top edge. The sections are labeled with the number 85' at the top, 85 in the middle, and 72 at the bottom. The bottom-most section is shown in a partially exploded view, revealing internal components labeled 76, 75, 83, 77, 82, 81, and 73.

 tion of Illinois

Application January 8, 1940, Serial No. 312,849

16 Claims.

(Cl. 101—419)

This invention relates to duplicating machines and the like and more particularly to print-receiving and separating equipment for use with such machines. It has for its principal object to provide improved apparatus of the character designated which will expedite the collection of copies and the removal thereof from the duplicating machine, which will greatly reduce damage to and loss of copies caused by offset and smearing, and which will generally increase the efficiency and reduce the cost of separating and drying such copies.

One of the specific objects of my invention is to provide apparatus in which prints from a duplicator are delivered into a combined receiving and separating unit, which may be quickly and easily removed from the machine when full and which will serve to support the prints during drying thereof while the run is continued with other units.

Another object of my invention is to provide print-receiving apparatus which may be operated either with or without the separating units as desired, and which may be so adjusted that the prints are delivered at a substantially constant level in either case.

Another object of the invention is to provide a device in which separating interleaves are successively fed to the proper level for receiving a print, and are thereafter lowered to clear the following leaves without being brought into immediate contact with the preceding leaves and prints.

Another object of the invention is to provide a device in which the first interleaf will always be fed to print-receiving position before the first print is delivered by the duplicator, and in which the movement of the receiving unit and the feeding of interleaves is stopped when the printing of copies by the duplicator is interrupted.

Another object of the invention is to provide a device having means to stop the supply of impression paper to the duplicator when the print-receiving unit has been filled.

Other objects of the invention will appear from the following description taken in connection with the drawings, which form a part of this specification and in which:

Fig. 1 is a perspective view of a duplicating machine of well-known construction, showing the application of my improved interleaving device thereto.

Fig. 2 is a perspective view of the interleaving device shown in Fig. 1 removed from the dupli-

cating machine, the view being taken from the feed-end of said device.

Fig. 3 is a plan view of part of the interleaving device of Figs. 1 and 2, partially in section and partially broken away to more clearly show the construction.

Fig. 4 is a sectional view taken substantially on the line 4—4 of Fig. 3.

Fig. 5 is a sectional view taken substantially on the line 5—5 of Fig. 3, showing the removable receiving and separating unit in position.

Figs. 6 and 7 are fragmentary sectional views taken substantially on the lines 6—6 and 7—7 of Fig. 3 respectively, parts of the associated duplicator being shown in Fig. 7.

Fig. 8 is a fragmentary sectional view taken substantially on the line 8—8 of Fig. 6.

Figs. 9 and 10 are fragmentary sectional views taken substantially on the lines 9—9 and 10—10 of Fig. 3 respectively.

Fig. 11 is a detailed plan view showing the separating and actuating fingers.

Fig. 12 is a perspective view showing the construction of the removable receiving and separating unit, and

Fig. 13 is a perspective view showing said unit removed from the device and loaded with prints in drying position.

Figs. 14, 15 and 16 are detail views showing the preferred construction of a single separating member or leaf.

Referring to the drawings, at 5 in Fig. 1 is indicated generally a duplicating machine, mounted on any suitable support and having the usual side frame members 6. A printing cylinder 7 is rotatably supported between the members 6, and an impression roller 8, shown in Fig. 7, is rotatably mounted in suitable bearings at the ends of arms 9 which are pivotally mounted as at 11 to the frame members 6. This impression roller is adapted to cooperate with the cylinder 7 to form the printing couple of the duplicator. The cylinder 7 is adapted to carry a stencil 12 to which ink is supplied so that impression sheets are printed in contact with the stencil when passed through the printing couple by suitable paper-feeding mechanism, a part 13 of which is indicated in Figs. 1 and 7. A pulley 14 is operatively connected to the cylinder 7 in driving relation thereto and is actuated through a belt 15 from any convenient source of power, not shown, which may be an electric motor. Also connected to the cylinder 12 is a sprocket 16, which is adapted to drive another sprocket 17 through a connecting chain 18. This chain is sufficiently

slack to permit easy removal from the sprockets and the slack is taken up by an adjustable idler sprocket 19 mounted on the side frame 6 of the machine. As stencil duplicating machines of the type shown are well known in the art to which this invention relates, further description of the construction and operation of this machine is unnecessary.

The interleaving device of this invention constitutes a separate unit 20, mounted on and readily detachable from the duplicator 5. As best shown in Fig. 2, it comprises a frame including side members 21 which are rigidly connected by cross-members 22 and spaced thereby to readily fit between the side frame members 6 at the rear or delivery end of the duplicating machine. The side members 21 are formed at their rear ends with upwardly projecting portions 23 and 24, of which the latter are inclined toward the rear of the device. The portions 23 are adapted to be secured as by bolts 25 to the duplicator frame members 6, and one of the cross members 22 is provided with a bracket 26, shown in Fig. 4, adapted to rest on the bed of the duplicator at the front end thereof. This member 22 is also secured by bolts, not shown, to the duplicator frame whereby the interleaving unit 20 is removably positioned on and secured to said machine.

Transversely disposed between and mounted in suitable bearings on the side members 21 is a shaft 31, on which is mounted a number of spaced print-forwarding rollers 32 adapted to engage the prints P as these are delivered in succession by the duplicating machine and advance them to the receiving device. Shaft 31, and with it the rollers 32, is continuously driven in cooperation with spaced idler wheels 33 preferably formed with knurled rims adapted yieldably to engage the edges of the prints and to maintain them in contact with the rollers 32. For this purpose the wheels 33 are journaled on stub shafts 34 in bell crank arms 35, which arms are pivotally mounted as by pins 36 on bracket members 37, best shown in Figs. 9 and 10, the arms being provided with springs 38 which tend to turn on pins 36 in a direction to urge wheels 33 toward rollers 32. In order that the wheels 33 may be laterally adjusted to the size of the printed sheets, the bracket members are slidably mounted on a rod 39 of square section, removably mounted between the arm members 23, and may be clamped in adjusted position on said rod by means of thumb screws 41.

The shaft 31 is provided near one end with a pinion 42 in mesh with a gear 43 journaled on a stub shaft 44 mounted on an adjacent side member 21. Integral with the gear 43 is a pinion 46 which is in mesh with a gear 47 secured on a shaft 48 which extends transversely between and is journaled in suitable bearings carried by the side members 21. The gear 47 is in mesh with a gear 49 on a shaft 51, which is journaled at its inner ends in a suitable bearing mounted on a bracket 52 secured to the cross member 22. Outwardly of the gear 49 the shaft 51 is journaled in and projects through a bearing 53 in the side member 21, and further projects through an aligned opening in the frame member 6 of the duplicating machine, and carries on its outer end the driven sprocket 17. Accordingly, the roller shaft 31 is continuously driven from the duplicating machine through the gear train 42, 43, 46, 47, 49, the shaft 51, the sprocket 17 and chain 18.

Delivery of the prints to the receiving unit is completed by a kicker mechanism adapted to engage the trailing edge of each print as it leaves the rollers 32. This mechanism, best shown in Figs. 3 and 4, comprises a pusher 56 formed at one end with ears 57 which are pivotally supported as at 58 on brackets 59 on the rear cross-member 22. The pusher 56 is actuated by means of a link 61 pivotally connected thereto at one end and pivotally connected at its other end to a lever 62 which in turn is pivotally mounted on a pin 63 carried by a bracket 64 on the cross-member 22. The lever 62 is provided intermediate its ends with a roller cam follower 65 adapted to be actuated by a cam 66 mounted on the cross shaft 48. The pusher operating linkage is retracted, and the cam follower maintained in contact with cam 66 by means of a spring 67 connected to the lever 62.

Thus it will be seen that my device includes a sheet-forwarding means by which prints are discharged from the printing couple of the duplicator, are received between continuously driven rollers 32 and cooperating wheels 33, and by them advanced to the print-receiving device, final delivery of each print into said receiving device being insured by action of the pusher 56 on the rear edge of said print.

The print-receiving unit 71 is removably supported in operative position behind the forwarding means during the operation of receiving prints, as best shown in Fig. 5. As also shown in Figs. 12 and 13, this unit comprises a bound stack or book of print-separating interleaves 72 between which leaves the successive prints P are delivered. The leaves 72 may be made of any suitable material, such as cardboard or straw board which has sufficient strength, resilience and porosity for the purpose. Each of the leaves 72 has a butt portion of reduced width forming shoulders, as indicated at 73, and the butt portion is preferably scored or weakened so that it may be readily folded on itself to form a thickened portion 74 adapted to space the adjacent leaves. Each of the leaves 72 is perforated adjacent the butt portion with spaced openings 75, preferably of semi-circular contour, to receive binding strips 76 by which the stack of leaves is secured to a binding frame 77.

The frame 77 is a rectangular structure of open box-like form having side members 78 and top and bottom members 79 adapted to engage and bind the butt portions of the leaves 72 into the form of a book. The side members 78 are formed with flanges 81 adapted to engage the leaf shoulders 73, and the members 79 are provided with flanges 82 to which the ends of the strips 76 are removably secured as by the screws 83. The openings 75 are so placed that the strips 76 which pass through them bear on the folded ends of the butt portions 74 so that the leaves are rigidly bound at their butt ends and are somewhat separated, as for example by twice the thickness of a leaf, to define a space of material depth for reception of a print. The flanges 82 are formed with attaching members 84 by which the unit 71 is positioned on the device, and which also serve as handles.

The leaves 72 are also formed at their sides with notches 85, which are symmetrically aligned laterally of the leaf as best shown in Fig. 13. These notches are spaced from the free end of the leaf so as to stagger the notches in successive leaves, the notches of the alternate leaves being in line, and the book 71 is so bound that

the outside leaves are identical, for a purpose presently to be described. Preferably the outside leaves and all the alternate leaves between them have the notches 85 nearer to the end than the other leaves, as shown in Figs. 12, 14 and 15, and such leaves may be conveniently distinguished by an end thumb notch 85'. It will be understood that book units 71 of different lengths may be provided to accommodate the various standard sizes of prints. Such books differ only in the length of their leaves 72 from the shoulders 73 to the notches 85.

The unit 71 is supported in print-receiving position on a table 86, mounted for vertical movement at the front of the device between the side members 21, and formed with a downwardly disposed end flange 87 and side flanges 88. Rigidly secured to the flanges 87 and 88 at each side of and below the table 86 are vertically disposed supports 89, on which are mounted rollers 90 adapted to roll between the flanges of vertically disposed guide channels 91 secured to one of the cross-frame members 22, and spaced at their lower ends by a cross-member 92 by which the table 86 is guided in its vertical path. The sides of the table 86 above the side flanges 88 are formed with longitudinally disposed channels 93 in which is slidably mounted an extension 94 forming a part of the table for the accommodation of longer prints, the table having suitable means such as a thumb nut 95 at one side by which the extension 94 may be clamped thereto in adjusted position. The extension 94 is provided near its end with a retractable stud 96 adapted to enter a hole 97 in the attaching portion 84 of the receiving unit 71, as shown in Fig. 5.

The table extension 94 is provided with an end gate 98, having side flanges 99 by which it is hinged to the end flange of the extension as at 101, and having a bottom web 102 adapted to bear on the top of the table extension when the gate 98 is in its vertical position. A latch bar 103 is pivotally mounted on the gate 98 as at 104 and projects at its lower end through a slot 105 in the extension 94, having at its end a notch 106 adapted to engage a pin 107 secured to the under-surface of the table extension in any suitable manner. The upper end of the latch bar 103 projects through a slot 108 in the upper flange of the gate 98 and is formed with an offset portion 109 adapted to pass through a notch 111 formed in the frame member 79 of the unit 71 and engage behind said member. The bar 103 is urged toward locking position by a spring 112 and may be provided with a handle if desired.

Thus it may be seen that having adjusted and secured the table extension 94 in the position corresponding to the particular unit 71 to be used, said unit is readily positioned on the table by placing the hole 97 over the stud 96 and then swinging the gate 98 on its hinges 101 toward a vertical position until the portion 109 of the latch bar 103 can be passed through its notch 111. Pivotal movement of the bar 103 then locks the frame 71 to the gate 98, and latches the gate 98 in upright position on the extension 94, thus rigidly supporting the butt of the unit 71 in vertical position at the end of the table.

The table 86 is adapted to be lowered in a step by step motion in timed relation to the delivery of prints by the duplicator. To effect this a lowering device is provided comprising an endless chain 116 passing in vertically disposed

reaches over an upper sprocket 117 and a lower sprocket 118, of which the latter is journaled on a stud 119 mounted in the lower cross-member 92, while the former is secured to a shaft 121 journaled in a suitable bearing 122 in an upper cross-frame member 22. The descending reach of the chain 116 passes through a guide 123 secured to the flange 87 of the table 86, which guide is provided with a slot 124 through which projects the end of a dog 125 pivotally mounted on the flange 87. The dog is preferably urged into chain-engaging position by a suitable spring, not shown, and may be provided with a handle 126, projecting through a slot into the flange 87. 15 The table may be manually raised to its uppermost position, the spring-pressed dog 125 sliding over the chain to permit this.

The shaft 121, and with it the sprocket 117 and chain 116, is periodically driven in the direction to lower the table 86 in timed relation to the duplicator by means which permits the amplitude of the periodical movement to be selected. This driving means, best shown in Figs. 9 and 10, includes a worm wheel 127 fixed to the shaft 121 and in operative engagement with a worm 128 fixed on a cross-shaft 129 which is journaled in bearings carried by brackets 131 mounted on the front face of the cross member 22. Secured to shaft 129 is a ratchet wheel 132 actuated by a spring-pressed pawl 133 pivotally mounted on a lever 134, which in turn is mounted for pivotal movement about the shaft 129, and which is connected by a link 135 to an arm 136. The lower end of arm 136 is pivotally mounted on a rock shaft 137 extending between the side frames 21 and is provided with an extension 138 to which is attached a spring 139 tending to urge the arm 136 forwardly or to the left as shown in Fig. 9. Secured to the shaft 137 adjacent the arm 136 is an arm 141 having a lug 142 adapted to engage the arm 136 and having an arm 143 provided with a spring 144, similar to the spring 139. The upper end of the arm 141 is provided with a roller cam follower 145, urged by the action of the spring 144 into operative engagement with a cam 146 mounted on and rigidly secured to the cross shaft 48. Thus it will be apparent that as the shaft 48 is driven by its gear 47, the arm 141 will be oscillated about its axis by the cam 146 in timed relation to the duplicator, and will in turn move the arm 136, against the action of spring 139 so as to oscillate the pawl lever 134 in the same time.

55 The lower end of arm 136 is secured to a sleeve 147, journaled on the shaft 137, on which is mounted adjacent the side frame member 21 an upwardly disposed arm 148, which oscillates with the arm 136. To adjustably control the feed of the pawl 133, and thereby the extent to 60 which the table is lowered on each cycle of the machine, a latch lever 149 is pivotally mounted on the side frame 21 and projects near its lower end through a slot 151 therein and preferably terminates in a handle, not shown, which may be adjustably secured to the side frame 21 in any convenient manner. As best shown in Fig. 5, a latch dog 152 is pivoted to the lever 149 near its upper end, as at 153, and is urged by a spring 65 154 into a position against a stop 155 such that its lip 156 will project into the path of and limit movement of the arm 148. Such limitation of movement in turn limits the movement of the arm 136 and restricts the stroke of the pawl 133, thus lessening the extent of downward movement 70 75

of the table. Movement of the latch lever 149 into its other position of adjustment, however, shifts the latch dog 152 into a position to clear the arm 148 so that the movement of this arm and the arm 136 is not limited, the pawl 133 makes a full stroke and the table is lowered a full step. Thus the lowering action may be readily adjusted to either of two positions; one for feeding prints to the unit 71 in which case a relatively larger downward movement is required for each cycle of the machine, and the other for feeding prints directly to the table functioning as a receiving tray, in which the downward movement should be much smaller.

The print-receiving unit 71 is supported above the table at its bound or butt end, as previously described, and the stack of leaves 72 is also supported, intermediate its ends, in a slightly higher position so that the leaves 72 are somewhat curved upwardly from butt to tip against their own natural resilience and weight, which urge them downward toward the table. The supporting means is adapted to release the leaves in succession from the bottom of the stack in timed relation to the duplicator so that each print that is forwarded by the rollers 32 is delivered onto a leaf 72, which is then lowered to permit the next leaf to be dropped into print-receiving position.

The leaf-supporting and dropping means is in part mounted on the upwardly-inclined portions 24 of the side members 21 and comprises laterally disposed fingers 161, pivotally mounted for oscillatory movement on journals 162 supported in ears 163 formed at the upper ends of the members 24. The fingers 161 are arranged in pairs, one member of each pair being disposed on each of the members 24 adjacent a member of the other pair, so that the fingers 161 of each pair are oppositely disposed at the side of and above the table 86. The fingers 161 of each pair are adapted to oscillate in unison and the pairs are adapted to oscillate alternately. For this purpose each finger 161 is formed with a portion 164, pivotally connected to a tension link 165, which link is urged upwardly by a spring 166 tending to depress the end of the connected finger.

The lower ends of the links 165 are provided with studs 167, each adapted to be engaged by the hooked end 168 of a rocker lever, a pair of such rocker levers 169 and another pair 171 being provided to actuate each pair of the fingers 161. The rocker levers 169, corresponding to one of the pairs of fingers 161, are secured to a shaft 172, journaled at its ends in the side frame 21, while the levers 171 corresponding to the other pair of fingers are fixed to a sleeve 173 journaled on the shaft 172 between the levers 169. The shaft 172 and the sleeve 173 are provided with arms 174 and 175 respectively, which may be extensions of the levers 169 and 171 at one side of the device, each of which carries at its end a cam follower 176 which is in operative engagement with a cam 177, the two cams being mounted on and secured to the shaft 48 in a phase relation such as to provide the desired alternate operation of the pairs of fingers 161.

It will be understood from the foregoing description that the stack of leaves is supported by that pair of fingers 161 which is out of registry with the notches 85 of the lowermost leaf. As the lowermost leaf is dropped by the depression of its supporting fingers, its notches enable it to clear the other pair of fingers which are rising to support the succeeding leaf and the remainder

of the book. The invention contemplates that the unit 71 may be placed on the table with either side up. The initial leaves are identical and have their notches 85 nearer the free end than the other alternate leaves, so that when the unit is first placed in position, the stack of leaves is supported by that pair of fingers 161 furthest from the duplicator. Operation of the other pair of fingers 161 is so correlated with and controlled by the operation of the duplicator, by means presently to be described, that upon the beginning of a run or upon resumption thereof after a stop, the lowermost leaf 72 is always dropped before a print is fed to the forwarding rollers 32, such correlation being effected by a connection between the dropping mechanism and the impression roller control presently to be described.

Each leaf released from the stack by the fingers 161 is first dropped to the proper level for receiving its print, which is delivered into the space immediately above it. As soon as this is accomplished the leaf is lowered to a second position slightly below the print-receiving level, where it is retained while the following leaf is dropped. While the print is being delivered to the space above this following leaf, the preceding first-mentioned leaf is dropped to its third or final position which is below the delivery level and is determined principally by the resilience of the leaf and the weight upon it. To control the leaves as they pass through these successive positions, a double pair of leaf-intercepting fingers 181 and 182 is employed.

The fingers 181 are formed at the ends of longitudinally disposed extensions 183 of a yoke 184 and are adapted to be projected rearwardly of the print-forwarding rollers 32 into the path of the leaves 72. The extensions 183 are provided with slots 185 cooperating with pins 187 whereby they are guided in an approximately horizontal path slightly below the feeding level. Secured to the yoke 184 is an upwardly projecting member 188, best shown in Fig. 4, which is pivotally connected as at 189 to the pusher actuating lever 62, whereby the yoke, and with it the fingers 181, is oscillated in timed relation to the machine.

The fingers 182, which are disposed beside and somewhat below the fingers 181, are formed on extensions 191 of a yoke 192, and are pivotally connected near their rear ends to radius links 193 pivotally supported as at 194 on suitable brackets and provided with springs 196 adapted to urge the fingers 182 toward the rear end of the machine into the path of the leaves 72, as best shown in Fig. 9.

Secured to the yoke 192 intermediate its ends is an actuating arm 197, the end of which is formed with an upstanding portion provided with a slot 198 of which the rear portion is wider than the forward portion, defining a notch 199. The yoke 192 is urged in a rearward direction by a spring 201 connected, as best shown in Fig. 10, to an ear formed on the arm 197, and is retracted by a pin 202, adapted to engage the notch 199, which pin is carried by a lever 203 pivotally mounted on a suitable bracket 204 on the frame member 22, as shown in Fig. 4. Mounted on the lever 203 is a cam follower 206 adapted to engage a cam 207 secured to the shaft 48 adjacent the arm 197, yoke 192 and fingers 182 are oscillated against the springs 201 and 196 in timed relation to the machine.

The pairs of fingers 181 and 182 do not operate

in unison or have similar cycles of movement, but are separately actuated for different purposes. The fingers 181 move forwardly in synchronism with the pusher 56 and pass over the print P which is being forwarded by the pusher in time to intercept the leaf next to be dropped. While said fingers 181 are in their advanced position the fingers 182 are retracted to drop to its final position the leaf previously fed, and are returned immediately to their advanced position rearwardly and slightly below the level of the fingers 181. Upon the following retraction of said fingers 181 the leaf is transferred from the feeding level to the level of the fingers 182, where it is held until it is ready to be dropped on the next cycle.

A means is also provided whereby leaves 72 will not be dropped and the receiving table will not be lowered when the machine fails to forward prints for any reason, as for example, when the supply of impression paper is exhausted. To this end a lever 209 is secured to the rock shaft 137 so that it is oscillated with said shaft in timed relation to the duplicator by the arm 141 and cam 146, as previously described. The upper end of the lever 209 is formed with a hook-shaped portion 210, best shown in Fig. 7, which is oscillated by the shaft 137 in an arc which extends beneath a pin 211 on one of the oscillatory supporting arms 9 of the duplicator impression roller 8. During normal operation of the duplicator the impression roller 8 is raised by its arms 9 whenever a sheet is being fed to the printing couple, which movement enables the hook-portion 210 to clear the pin 211 on its forward travel and permits the spring 144 to rock the shaft 137 as determined by the cam 146. However, in the event that no sheet is fed to the printing couple, the impression roller arm is not raised, so that the pin 211 lies in the path of and prevents the return movement of the portion 210, thus restricting movement of the lever 209 and the shaft 137.

The rocker lever 171 at one side of the device is provided, as shown in Fig. 6, with an extension 212, the forward end of which terminates in an abutment 213, disposed over the shaft 137, which normally oscillates in a generally vertical arc in response to movement of the lever. Pivotally mounted on the shaft 137 is a latch member 214 provided with a notch 216 and an extension 217, which extension is connected by a spring 218 to an arm 219 fixed on the shaft 137, the extension 217 being urged by the spring into contact with an abutment 221 on the arm 219. During normal feeding operation the timing of these parts is such that the notch 216 is swung clear of the abutment 213 on each cycle of the device, permitting movement of the extension 212, and accordingly, movement of the corresponding fingers 161. When oscillation of the shaft 137 is restricted, as described, the latch 214 is not retracted, the notch 216 engages the abutment 213 on its succeeding down stroke and restrains movement of the lever 171, which stops movement of the fingers 161 nearest the end of the unit 71, and prevents the dropping of leaves.

To an intermediate portion of the sleeve 173, which connects and oscillates the lever 171, is secured, as by a suitable clamp, an upwardly disposed arm 222, which carries at its upper end a pin 223. This pin extends under and is adapted to raise the arm 197 with its slot portion 198 on each cycle of the mechanism. In normal feeding operation the arm 197 is lowered by the pin 223

under the action of the spring 201 in time for the pin 202 to engage the notch 199 and thus retract the yoke 192 and the fingers 182. When oscillation of the shaft 137 is restricted as described, the pin 223 is held in its highest position, the arm 197 is not lowered and the pin 202 does not engage in the notch, so that the yoke and the fingers are not retracted but remain in their leaf-intercepting position until normal operation is resumed.

At the same time when the shaft 137 is restrained, as described, the cam follower 145, which is mounted on the arm 141, secured to said shaft, is held out of engagement with its cam 146, so that the associated arm 136 is not actuated, the pawl 133 does not operate the ratchet wheel 132 and the device for lowering the table 86 is not operated until normal operation is resumed.

Means is also provided for stopping the printing operation of the duplicator when the table 86 has reached the lower limit of its travel. For this purpose the table 86 is provided with a pin 224 which projects laterally from the support 89 below the level of the table, as shown in Fig. 8. Just before the table reaches the lower end of its travel, this pin 224 is adapted to contact and actuate a lug 225 which is secured to a vertical slide 226 mounted for limited vertical movement on brackets 227 on the guide channel 92, as by screws 228, passing through slotted holes 229 in the slide. The upper end of the slide is connected as at 231 to one arm of a bell crank lever 232, pivotally mounted as shown in Fig. 6 at 233 on the side member 21 and urged by a spring 234 in a direction tending to raise the slide. This slide 226 is also provided with a latch member 235 arranged to cooperate with the hook end 236 of a latch bar 237, which is slidably mounted in any convenient manner on the channels 92 and urged by a spring 238 into engagement with the member 235. The bar 237 is provided with a suitable handle, not shown, located in any position convenient to the operator of the machine.

Another arm of the bell crank lever 232 is provided with a pin 239, cooperating with a slot 241 formed in a link 242, the lost motion of said connection being taken up by a spring 243. The lower end of the link 242 slidably supported on the frame 21 and guided by a stud and slot connection 245 as shown in Fig. 7, is disposed adjacent to the path of a latch member 244 movably mounted as by pin and slot connection 246 on the side frame member 21. The member 244 is urged into its highest position by a spring 247 so that its upper end is disposed in the path of any suitable part of the duplicator paper-feeding mechanism, such as is indicated at 13. It is periodically retracted or pulled down against the action of the spring 247 by means of a pin 248, projecting therefrom near its lower end and disposed in a slot 252 formed in a rocker lever 251. The rocker lever 251 is pivotally mounted as at 253 on the frame member 21 and is oscillated in timed relation to the device against the action of a spring 254 by means of a cam extension 255 formed on the end of the lever 169, which extension is adapted to contact and actuate a pin 256 mounted on an arm of the lever 251. In normal operation the latch member 244 moves in a substantially vertical path in time with the duplicator feed arm 13 without affecting the motion of such part. However, when the link 242 is moved through

the intervening linkage by reason of the pin 224 striking the lug 225 at the lower end of the table travel, the lower end of said link is moved into the path of movement of the latch 244 restraining its downward movement. Its upper end then contacts and restrains movement of the duplicator feed arm 13 so as to prevent the further feeding of paper to the printing couple of the duplicator until the table is restored to its initial position in readiness for continued operation.

The operation of the device will be apparent from the foregoing description. Prints discharged in succession from the printing couple of the duplicator 5 are picked up by the forwarding rollers 32 and delivered into the print-receiving spaces between the leaves 72 of the book unit 71. This unit is rifled in time with the discharge of prints from the duplicator so that each of the spaces is opened in turn to receive its print. The rifling is actuated by releasing the lower leaves of the flexed book from the supporting fingers 161, and the descent of such released leaf is effected in stages by means of the intercepting fingers 181, 182 so that each leaf is held in turn at the proper receiving level while the print is forwarded into the space above it. During such feeding, the book unit 71 is progressively lowered to maintain the receiving level substantially constant throughout the run.

It will be observed that the leaves of the book 71 are spaced at their bound ends so that after a print is deposited in a given space and the next leaf is released, there is no immediate or forceful contact between such next leaf and the freshly printed surface. In effect, the spaces between the leaves 72 form individual trays in which the prints are supported during the drying interval, and in which there is complete access of air to the printed surface. In this manner the prints may be dried with a minimum of loss from smudging and with complete freedom from offset. The apparatus may also be used without a receiving unit, in which case the prints are fed to the table 86 which then functions as a receiving tray, and the rate of lowering of the table may be adjusted to meet the requirements by limiting movement of the pawl arm 148.

The feeding of impression sheets to the duplicator is automatically shut off when the book is full of prints and the table has reached the bottom of its travel. This is effected by means of the latch member 244 which is actuated, through the linkage described, from the pin 224, so that prints will not continue to be fed onto the top of the book after it is full. When the book unit has been filled with prints, it may be quickly and easily removed from the table 86 and placed on its butt end on any convenient support, in the upstanding position indicated in Fig. 13. In this position it functions to support the separated prints while exposing them freely to the air during the time necessary for them to dry. As soon as the book unit 71 is removed from the table, another unit may be placed in position and the run of prints resumed, and such changing of books can be quickly and easily accomplished without appreciable loss of printing time. The prints, when dry, may be easily removed from the book by their exposed marginal edges, as will be readily understood.

It will also be evident that the device provides control means adapted to conserve the time of the operator and to obviate the necessity

for continuous attention. Thus the release of leaves 72 is discontinued and downward motion of the table is stopped upon the failure of the duplicator to discharge prints, the operation of these controls being previously described. The arrangement of the notches 85 and the operation of the fingers 161 is also so correlated that the book may be placed on the table with either side up and the first leaf 72 will always be released before the first print is forwarded from the duplicator.

It will be understood that various forms of the invention other than those described above may be used without departing from the spirit or scope of the invention.

Having thus described the invention, what is claimed and desired to be secured by Letters Patent is:

1. A device for separating and supporting prints delivered from a duplicator or the like comprising means for forwarding successive prints at a fixed delivery level, a book of spaced leaves bound at one end, leaf-supporting means to maintain the unbound end of the book above said delivery level whereby the leaves are flexed upwardly, means actuating said leaf-supporting means to release the free end of the lowermost leaf in timed relation to the duplicator, and book-supporting means movable to position the last released leaf below said delivery level.

2. A device for separating and supporting prints delivered in succession from a duplicator or the like at a fixed delivery level comprising a book of leaves bound at one end, table means adapted to support and progressively lower said bound end, leaf-supporting and feeding means adapted to support the unbound end of the book above said delivery level and to successively release the lowermost leaf thereof, means to arrest each released leaf at a constant level to define a print-receiving interspace, and means for forwarding prints from the duplicator to successive interspaces.

3. A device for receiving and separating prints discharged from a duplicator or the like, comprising a bound book of spaced leaves, means to rigidly support the bound end of said book, means including oscillatory fingers to support the leaves of said book in elevated position, means to alternately oscillate said fingers to release the lower leaf while supporting the remainder of said leaves, intercepting members adapted to arrest movement of each released leaf in print-receiving position to define a space, and means to forward prints in succession from the duplicator to said spaces.

4. A device for receiving and separating prints discharged from a duplicator or the like, comprising a bound book of spaced leaves, pairs of pivoted fingers disposed beneath and at the sides of the book, means to alternately oscillate the fingers of each pair in unison between a substantially horizontal position and a substantially vertical position whereby the fingers of one pair release the lowermost leaf while the fingers of the other pair support the remaining leaves, and means to feed a print from the duplicator into the space between each released leaf and the remainder of the book.

5. A device for receiving and separating prints discharged from a duplicator or the like, comprising a bound book of spaced leaves, pairs of laterally disposed fingers pivotally mounted beneath and at the sides of the book, springs connected to urge said fingers toward their upper-

most position, means actuated in timed relation to the duplicator to alternately depress in unison the fingers of each pair against said springs to release the lowermost leaf while the fingers of the other pair are elevated by the springs to support the remainder of the book, and means to feed a print from the duplicator into the space above each released leaf.

6. A device for receiving prints discharged from a duplicator or the like, comprising a table having an end gate and adapted to operate as a receiving tray for prints, a print-separating device, means carried by said end gate to removably secure said separating device on said table, means including ratchet gearing to lower said table in periodic steps in timed relation to the duplicator, and means to adjust the amplitude of movement of said gearing.

7. In combination with a duplicator having sheet-feeding mechanism, a latch adapted to lock said mechanism out of operation, a print-receiving and separating device comprising a book of spaced leaves defining spaces adapted to receive prints, a table carrying said book, gearing to lower said table as prints are delivered in said spaces, and linkage actuated by the movement of said table near the end of its travel to operate the latch for said sheet-feeding mechanism.

8. In combination with a duplicator having a printing couple operated therefrom, a print-receiving and separating device comprising a book of spaced leaves defining spaces adapted to receive prints, leaf supporting means driven from the duplicator and periodically depressed to riffle said book in time with the duplicator to open said spaces for the reception of prints, and means actuated by said printing couple to lock said riffling means out of operation upon failure of the duplicator to discharge prints.

9. A device for receiving and supporting prints and the like, comprising a bound book of spaced leaves, notches in the side edges of said leaves, the notches of alternate leaves being aligned and the notches of adjacent leaves being staggered, means to riffle said book including vertically oscillatory fingers adapted to engage the leaves adjacent said notches, and means for alternately depressing said fingers in predetermined order.

10. A device for receiving and separating prints or the like, comprising a bound book of spaced leaves, means including oscillatory fingers to support said leaves in flexed position, means including cams to alternately oscillate said fingers whereby said leaves are successively released, intercepting members adapted to arrest movement of each released leaf in print-receiving position, means including cams to actuate the intercepting members, and common means driving all of said cams whereby the fingers and intercepting members are operated in timed relation.

11. A device for receiving and separating prints discharged from a duplicator comprising a bound book of spaced leaves, pairs of depressible fingers pivotally mounted at the sides of the

book, means actuated in timed relation to the duplicator to alternately depress the fingers of each pair to release the lowermost leaf while the remainder of the book is supported by the other pair, a movable table to support the book, gearing to progressively lower said table in steps, and common means for driving said gearing and said finger operating means.

12. Device for receiving and separating prints discharged from a duplicator or the like, comprising a bound book of spaced leaves, depressible fingers operable to support the unbound end of the book and to successively release the lowermost leaf to form a print-receiving space, a movable table to support the bound end of the book, means to lower said table in successive steps, and gearing connecting and driving the fingers and the table lowering means in timed relation.

13. A device for separating and supporting prints delivered from a duplicator or the like, comprising a book of leaves, each leaf being materially spaced at one end from the adjacent leaves, a rigid binding for said book at the spaced ends of the leaves to form a stable base on which the book may rest and adapted to support the spaced leaves in vertical print-drying position, and means to also support said book in flexed position on its side, said supporting means being operable to release the flexed leaves successively in timed relation to the duplicator whereby the interleaf spaces are widely opened into print-receiving position.

14. A device for separating and supporting successively delivered prints and the like comprising a book of leaves, spacing members between the leaves adjacent their butt ends, a frame binding the butt ends of the leaves and the spacing members, and strap members passing through said leaves adjacent the spacing members adapted to secure the spaced leaves in the frame, said frame and spacing members being adapted to hold the spaced leaves in upstanding, print-supporting position.

15. A device for separating and supporting prints and the like during the drying thereof comprising a book of spaced leaves and a frame secured to and binding said leaves at one end to form a stable base for said book adapted to hold said leaves vertically in spaced parallel position to define print-drying spaces.

16. A device for receiving, separating and supporting successively delivered prints, comprising a book of leaves having butt ends of reduced width defining shoulders, spacing means between said butt ends separating the leaves to define print-receiving spaces, a frame clamping said leaf butts and spacing means and engaging said shoulders to support the leaves in upstanding position, spaced perforations in the leaves substantially in the line of the shoulders, and straps removably secured to said frame and passing through said perforations in contact with said spacing means to retain the leaves in the frame, said straps forming end stops for the prints.

ERNEST J. BRASSEUR.
